BY Wilbur M. Stone
His ATTORNEY

UNITED STATES PATENT OFFICE

JOSEPH S. STRING, OF EAST ORANGE, NEW JERSEY

PORT LIGHT

Application filed February 15, 1929. Serial No. 340,257.

This invention relates to improvements in port lights and more particularly to the construction of port hole covers and the means of fastening these shut. Among the objects 5 of the invention is to provide a cover having yieldable packing adapted to be pressed against some suitable portion of the frame work and a locking device carrying means for applying pressure to the cover at widely 10 separated points for holding the cover securely closed and compressing the packing. The packing serves the twofold purpose of cushioning the glass carrying frame and of sealing the port hole. Another object is to 15 provide means for quickly engaging the locking device which is securely fastened at the leisure of the operator by the actuation of the pressure applying means.

In the accompanying drawings one practicable embodiment of my invention is illustrated, in which drawings Figure 1 shows in perspective the port light detached and in closed position. Fig. 2 is a cross sectional representation of the device represented in 25 Fig. 1, but mounted on the frame work of the ship and in a larger scale, and Fig. 3 is a face view of a port light of a shape differing from that shown in Fig. 1.

The cover for the port hole is shown in the 20 illustration in the form of a door having a metal frame 5, furnished with a light of glass 6, this being held in position by removable stops 7, and cushioned at all its points of contact with the frame by a bent over strip 8.

The door or cover is hinged to a metal 35 frame 9 which has a flange portion 10 for passing through the opening in the side of the ship, illustrated in the drawing by a pair of wooden timbers 11. The frame 9 also has a flat portion 12 adapted to rest against the flat outer side of the ship body. In the illustration this flat portion 12 is shown let into a recess and held in position by screws 13.

The frame 11 is shown carrying at one side 45 two sets of hinge members 14-14, each pair of which carries a pivot bolt 15 upon which bolts the hinge members 16 fast with the cover or door frame 5 are mounted. It will be noted, especially in Fig. 2, that the pivot 50 receiving opening 17 of hinge member 16

is elongated so as to not interfere with the movement of the cover when subjected to the pressure applying means presently to be described.

At the side of the frame 9, opposite each 55 of the hinges, there is formed an extension 18 to which is pivoted a clevis 19 which constitutes part of the locking device.

The outer side of the cover frame 5, i. e. 60 the lower side in the Fig. 2 illustration, is provided with a groove adapted to register 65 with the upstanding edge of the flange 10 where this protrudes inwardly beyond the inner face of the framing members 11. This groove is preferably wider by considerable 70 extent than the thickness or width of the flange 10. In this groove there is inserted some suitable packing or cushioning material 20 for engaging the extension of the flange 10.

The locking means is shown in the form of 75 a bar 21. One bar 21 only is illustrated in Fig. 3 in which the cover 5' is shown as circular. And the frame work upon which it is mounted, as represented by the flat portion 12', is also round. In the Figure 1 construction in which the parts are rectangular two bars 21 are employed. It will be seen that 80 each bar 21 has a pair of hinge members 22 which engages one of the pivot bolts 15. Preferably these hinge members 22 lie inside 85 of the hinge members 14 and lie on the opposite sides of the hinge member 16. This makes a very strong and rigid construction, as will be obvious.

The free end of the bar 21 has a hook 23 which is in position to engage the shackle 19 when the door is shut, and the locking bar 21 is brought into its initial locking position.

The bar 21 carries adjacent its respective 90 ends or in a position to overlie the packing material 20, pressure applying devices illustrated in the form of thumb screws 24. By means of these thumb screws, after the shackle 19 is engaged with the hook 23, the 95 cover may be securely pressed against the frame 9 to such an extent that water and wind cannot pass. A certain amount of cushioning is also afforded by this means of compression.

During the compression of the packing by the pressure applying means the cover is permitted to freely move relatively to the hinge pivot, this being permitted by the extension 5 17 in its hinge.

Not only do the packing 20 and the pressure applying devices 24 hold the cover securely in position, but the pressure also has the effect of securing the locking device.

10 With the parts in the positions illustrated in the drawing, when it is desired to unfasten the port light or cover, the operator releases the screws 24 which then make it possible to remove the clevis 19 from the hook 23, whereupon the operator may swing the bars 21 on their hinges which will then leave the cover, which is a form of the door, free to be opened as may be desired.

With this cover door open, when it is desired to secure it in position the operator closes the door into the position illustrated, swings the bar, or the pair of bars 21, across the cover and engages the clevis 19 with the hook 23 which will preliminarily hold the door closed, after which, at his leisure, the operator will apply pressure by turning in the screws 24 until the packing material 20 is sufficiently compressed to hold the door rigidly in position and prevent the entrance of 30 wind and water.

Although the details of but one form of the invention have been illustrated and described, yet it will be obvious that various changes may be made within the scope of the claims 35 without departing from the spirit of the invention.

I claim:

1. In a port light, the combination with a frame adapted for application to the port 40 hole of a vessel, the frame having at one side a hinge comprising a pair of hinge members supporting a pivot pin and at the opposite side an extension, and a clevis pivoted to such extension, of a cover having a hinge member 45 provided with an elongated opening and mounted on the pivot pin, a locking bar having a pair of hinge members located inwardly of the hinge members of the frame and interposed between such members and the hinge member of the cover, the locking bar being 50 provided at its free end with a hook for engaging the clevis, and a pressure applying screw carried by each end of the bar located in position for pressing the cover against the frame and the bar against the pivot pin and 55 the clevis.

2. In a port light, the combination with a frame adapted for application to the port hole of a vessel, the frame having at one side 60 a hinge member supporting a pivot pin and at the opposite side an extension, a clevis carried by such extension, a cover having a hinge member mounted on the pivot pin, a locking bar hinged to the frame, such bar being provided at its free end with a hook for engag- 65

ing the clevis, and pressure applying screw means carried by each end of the bar for pressing the cover against the frame and the bar against the clevis.

3. In a port light, the combination with a frame adapted for application to the port hole of a vessel, the frame having at one side a hinge comprising a pair of hinge members supporting a pivot pin and at the opposite side an extension, and a clevis pivoted to such extension, of a cover having a hinge member provided with an elongated opening and mounted on the pivot pin, a locking bar having a pair of hinge members located inwardly of the hinge members of the frame and interposed between such members and the hinge member of the cover, the locking bar being provided at its free end with a hook for engaging the clevis, and pressure applying means carried by the bar for pressing the cover against the frame and the bar against the clevis.

In witness whereof, I hereby affix my signature this 11th day of February, 1929.

JOSEPH S. STRING.
